DESIGN FOR A TYPEWRITING MACHINE

Myrtle R. Keller, Syracuse, N. Y., assignor to
L. C. Smith & Corona Typewriters, Inc., Syra-
cuse, N. Y., a corporation of New York

Application May 16, 1936, Serial No. 62,675

Term of patent 14 years

To all whom it may concern:

Be it known that I, Myrtle R. Keller, a citizen of the United States and resident of Syracuse, in the county of Onondaga and State of New York, have invented a new, original, and ornamental Design for a Typewriting Machine, of which the following is a specification, reference being had to the accompanying drawings, forming a part thereof.

In the drawings, Fig. 1 is a perspective view of a typewriting machine, showing my new design; and

Fig. 2 is a plan view of the keyboard of the said typewriting machine.

In the drawings the keys are lined for color.

The dominant feature of the invention resides in the keyboard and in the ornamentation on the keys.

I claim:

The ornamental design for a typewriting machine, as shown, and described.

MYRTLE R. KELLER.
